UNITED STATES PATENT OFFICE.

WILLIAM ELDON LEIGHTON, OF WEST PEMBROKE, MAINE.

SOUND-POST.

1,383,830.

Specification of Letters Patent.

Patented July 5, 1921.

Application filed May 5, 1920. Serial No. 379,041.

To all whom it may concern:

Be it known that I, WILLIAM E. LEIGHTON, a citizen of the United States, and resident of West Pembroke, in the county of Washington and State of Maine, have invented 5 a new and Improved Sound-Post, of which the following is a full, clear, and exact description.

In connection with stringed instruments, 10 and more particularly of the violin type, a sound post is necessary between the belly and back in order to connect these two portion of the instrument.

The back, being of denser wood, and 15 thicker, vibrates with greater rapidity and is affected to a large extent by the action of the E and A strings. In this connection, it might be well to state that these strings would be practically valueless without the 20 connection afforded by means of the sound post.

It has now been usual to interpose this member between the belly and back of an instrument of this type, at a point slightly 25 below the bridge in order to get the necessary resiliency, and it has been demonstrated that with this arrangement, half of the lower part of the sounding board is practically non-responsive.

30 The vibration of the strings is communicated to the sounding board through the bridge, and it would hence be logical to place the post directly under the bridge, but this has been heretofore impossible, in view of 35 the fact, as aforesaid, that a certain amount of elasticity was necessary.

Having this in mind, I have constructed a sound post which may conveniently be disposed in the position indicated, but which 40 is not necessarily limited to this adaption and by means of which the amplitude of the sound waves are given more carrying power together with a more resonant tone quality, and which post may conveniently 45 be utilized in connection with any number of different types of stringed instruments.

Referring now more particularly to the drawings which illustrate one practical embodiment of my invention.

50 Figure 1 is a side view partly in section, of a conventional type of instrument, such as a violin.

Fig. 2 is a sectional end view taken along the line 2—2 of Fig. 1, and,

55 Fig. 3 is an enlarged side view of a sound

post constructed in accordance with my invention.

In these views the reference numeral 5 indicates the belly of the instrument and 6 the back thereof, this instrument being in 60 the usual manner provided with strings 7 and a bridge 8 interposed between the strings and the upper face of the belly 5.

A sound post, fully shown in Figs. 2 and 3 is interposed between the inner face of 65 the belly and back, in the usual manner, with the exception that the same is positioned directly under the bridge 8.

The sound post conveniently includes a pair of fibrous strips of material 9, having 70 their ends glued, or otherwise secured together, their center portion being bowed outwardly and away from one another, as has been indicated by the reference numeral 10, it being noted that the strands of the 75 fiber extend longitudinally of the body portion of the strips.

By the construction afforded, a certain amount of resiliency is incorporated in the sound post. By this construction it will not 80 be necessary to rely upon the resiliency, which was at best an uncertain quantity, derived from mounting the conventional sound post at a point slightly in advance 85 of the bridge 8. This resiliency incorporated in my improved type of sound post is to be attributed to the bowed portion 10 which provides an opening in the center of the post, and it will be appreciated that by this construction the sound post will 90 transmit the vibrations to the sounding board in a more desirable manner permitting a free vibration on the part of the sounding board as a whole.

Obviously my sounding post may be associated with any desired type of instrument, to which it is applicable, and various modifications of structure might be resorted to without departing from the scope of my claims.

Having thus described my invention, what I claim as new and desire to secure by Letters Patent is as follows:—

1. A sounding post, including a body portion formed with an unobstructed opening 105 substantially intermediate its ends whereby said sounding post is rendered capable of a resilient action.

2. A sounding post, including two strips of fibrous material, the fiber of each of which 110

extends longitudinally of the body portion thereof, secured together adjacent their ends, and having their body portions spaced one from the other, whereby said sounding post 5 is rendered capable of a resilient action.

3. A sounding post, including two strips of fibrous material, the fiber of each of which extends longitudinally of the body portion

thereof, said strips being secured together adjacent their ends, their center portions 10 being bowed outwardly and away from one another whereby said sounding post is rendered capable of a resilient action.

4. A resilient sounding post.

WILLIAM ELDON LEIGHTON.
